CROWN CAPS FOR CONTAINERS

Ralph M. Berglund, Burlingame, Calif.

Application December 18, 1953, Serial No. 399,078

7 Claims. (Cl. 215—46)

This invention relates to an improved crown cap of the type which may be removed from the container without benefit of a separate implement. The invention is herein illustratively described by reference to its presently preferred form as applied to a conventional beverage bottle, but it will be appreciated that other applications are contemplated and that various changes and modifications in respect to details of construction of the cap may be made without departing from the underlying essentials involved.

The general concept of a hand-removable crown cap operating on the principle of rupturing the cap by a tearing action in order to break the seal of its gasket with the container mouth is not new. It has been embodied in caps with integral rigid levers and in caps with a flexible tear tab. The latter type proved the more promising due to their lesser bulkiness, lower manufacturing cost and better adaptability to use with conventional or only slightly modified crimping and bottle capping machinery. A common difficulty experienced with both types as heretofore developed, however, resided in the inadequate methods used for weakening the cap along a preselected tear line. This was usually accomplished by scoring the cap material to a desired depth, but to do so practicably with mass production methods so that all caps would possess uniform strength and rupturability was a very difficult matter. With common tinplate and other cap material in use, the scoring usually so weakened the cap blank that it would not stand up under the crimping operation, or the scored cap would not withstand the internal container pressures sometimes developed (i. e. occasionally more than 100 p. s. i. with carbonated beverages, especially during pasteurization), if at the same time the cap was sufficiently weakened to be torn open easily with the fingers by pulling on the lever or tear tab provided.

The present invention is directed generally to the solution of the foregoing problems. The value and commercial utility of a fully satisfactory hand-rupturable crown cap, evidenced in part by the many efforts to develop such, are not due in any small measure to the increasing use of cans and other single-use containers as replacements for the time honored but more expensive glass bottle. It has been evident that the convenience to consumers of a hand-rupturable crown cap for bottles could more than compensate for the higher cost of that type of container.

It is also a purpose of this invention to provide an inexpensive crown cap of the type described which can readily be manufactured with the use of existing or known production machinery and which can be used in existing bottling apparatus, with little or no modifications in either. The latter factor is of particular importance in view of the large present investments of the foodstuffs industries in such machinery.

Another object is the provision of a hand-rupturable crown cap in the manufacture of which it is a comparatively easy matter to establish and uniformly regulate the

2

rupture strength imparted to the completed cap. The means providing a line of rupture on the cap are such that no unduly critical manufacturing steps are involved.

In achieving the foregoing objectives the improved 5 crown cap has a slit and the severed edges of this slit are bonded together by a technique which imparts the desired low shear resistance to the joint for the hand-rupture operation, yet a sufficient strength to withstand the stresses of crimping, capping and container pressure. In the preferred form the slit edges are flanged 10 outwardly of the cap to receive a fillet of binder substance, such as solder, therebetween, the slit extending in a continuous line from the edge of the cap skirt, upwardly along the crest of one of the skirt flutes, thence radially inward across the top and terminating short 15 of its center. A tear tab formed as an integral extension of the skirt at a location immediately adjacent one side of the bonded slit provides a finger grip by which shear pressure is readily applied initially to the 20 end of the slit and then progressively along its length, until it has been torn for a sufficient distance to break the container seal. Normally the cap will be manufactured from the usual tinplate sheet material and the tear-line joint will be formed with a conventional solder, 25 preliminary to the blank cutting and crimping operations. However, it will be observed that in the invention in basic respects there is not necessarily a limitation to specific materials and manufacturing techniques.

The foregoing and other features, objects and advantages 30 of the improved crown cap will become more fully evident from the following description by reference to the accompanying drawings.

Figure 1 is a plan view of the improved crown cap as it appears just prior to the capping operation.

Figure 2 is a side elevation view of the cap.

Figure 3 is a transverse sectional detail of the filleted tear line or joint.

Figures 4 and 5 are different side elevation views 40 of the improved crown cap as crimped on the lip of a bottle.

Figure 6 is a perspective view illustrating use of the tear tab to break the container seal and remove the cap.

Figure 7 is a plan view of a strip of material from 45 which cap blanks are to be cut, and particularly illustrates the technique for forming the filleted tear line.

Figure 8 is a schematic diagram depicting a suitable mass production method for manufacturing the improved crown cap.

The basic crown formation illustrated in the drawings 50 is conventional, the cap 10 comprising a circular top plate 10a and the crimped slightly divergent skirt 10b formed integrally therewith. A cork disk 12 or equivalent gasket is retained within the skirt against the top. In a bottle capping machine this gasket is of course compressed against the bottle lip as the capping head descends 55 in the process of squeezing and permanently deforming the skirt 10b. The compressed skirt 10b is thereby molded into locking engagement with the usual cap-retaining rib formed around the bottle lip.

In accordance with the present invention a slit 14 is formed in the cap 10. The slit extends uninterruptedly from the skirt's lower edge, along the crest of one of the skirt flutes 10b' and radially inward across the top 10a, terminating appreciably short of the center 10c. The slit edges are flanged slightly outward along their full length to form a groove between them which receives a fillet 14a of solder or other suitable binder substance. For satisfactory accommodation of the sealing gasket 12 within the cap the exposed face of the fillet 14a is made substantially flush with the immediately adjacent surfaces of the cap interior. A tear tab 16 projects from the edge of the skirt 10b immediately adjacent the slit 14. Preferably the

tear tab is an integral extension of the skirt itself, having a length and width just ample for it to be grasped conveniently between the fingers. A dimple or indentation 16a formed in the tear tab near its projecting end enables it to be gripped with a firm hold and pulled without slipping between the fingers. With the cap on a bottle B the tear tab 16 lies unobtrusively close alongside the neck thereof (Figure 4). The convex side of the indentation 16a then lies against the bottle neck and is accommodated beneath the overhang of the usual reinforcing bead or rib encircling the bottle beneath its lip. Consequently the existence of the tear tab 16 adds little or no bulk to a capped bottle, so that the latter may be handled and stored in the usual manner.

It is important or highly desirable for purposes of strength that the soldered slit 14 extend less than half way across the top 10a. When this condition is observed the stress imposed on the soldered joint as a result of internal container pressure will be largely radial of the cap, hence in a direction lengthwise of the solder fillet, and the joint will withstand very high internal pressures. However, if the slit were to extend more than half way across the cap, it is apparent that the joint is required to assume a transverse loading and more readily tears apart as internal container pressure is increased. By observing the condition described, namely that the length of the slit be appreciably less than the radius of the cap (such as about $\frac{3}{4}$ the radius) the specific strength of the soldered joint between the slit edges need not be great, and as a result the joint will tear apart readily when the tear tab 16 is grasped and pulled outwardly and upwardly in order to open the capped container (Figure 6).

It will be evident that the specific strength of the soldered joint between the edges of slit 14 may be varied by any of different production control methods. For instance, the cross-sectional form and the spacing between the flanges of the slit edges will control the effective bonding area and the strength of a solder fillet received between the flanges. The type of solder used and the type of flux affect the tensile strength of the bond. Likewise the strength of the fillet may be varied by removing some of the solder material therefrom with a conventional wiper before the solder has set. Furthermore, the type and gauge of the plate material used in the cap will affect the strength of the joint, since the stiffness of the plate material is a factor.

In place of solder as the bonding agent used in forming a weakened tear line in the cap body certain thermoplastic or thermosetting adhesive substances may be applied between the slit edges. The type of bonding material selected would depend, of course, upon the required strength of the joint and upon the type of material used in the cap. In all cases, however, the tear line will be formed by first slitting the cap body in the manner indicated, and then forming a bond between the severed edges, preferably with the edges flanged to receive a fillet of binder substance therebetween.

A suitable manufacturing technique for producing the improved crown cap out of tinplate and with a solder fillet is illustrated in Figures 7 and 8. An elongated strip of sheet material from which the caps are to be cut is fed through the initial feed rolls and between elements which simultaneously cut a longitudinal slit and flange the slit edges in a single operation. These elements comprise a circumferentially grooved bucking roll above the strip and a cooperating rotary knife beneath the strip. The groove in the bucking roll accommodates the two flanges formed in the strip as the knife blade presses through the strip material. The annular knife blade occupies only a fraction of the circumference of the blade support, so that as the elongated strip advances between the rolls flanged slits of predetermined length are made in the strip at appropriate uniform interval spacings along the length of the slit.

A short length of strip material S having a slit with

flanged edges formed by the rotary knife is shown in Figure 7. In the same figure the dotted outlines O1 and O2 of the two cap blanks are also shown to indicate the relationship between the slit and the blanking die cutting edges 5 by which two caps may be cut economically from the length of sheet material S in which a single slit is formed having edges bonded together before the blanking and forming operations.

After passing the slitting and flange-forming knife, the strip material moves through additional feed rolls and through apparatus for applying the solder fillet between the flanged edges of the slit. As the strip advances beyond the second set of feed rolls the flanged edges are wiped by a flux roll, to cover the surface areas to be 10 soldered with a soldering flux, passed through a preheater which raises the temperature of the strip in order to receive the solder properly, and then passed through the soldering rolls which apply molten solder to form the fillet in the space between the slit flanges. Excess solder is 15 wiped off by the linen wiper roll before the strip passes through an air blast cooling unit. Finally the strip passes into the guides of a blanking and forming press by which the individual caps are cut and crimped in the intended manner. The specific details of the apparatus mentioned 20 above are not described since the techniques involved are generally well known in the art and since the particular techniques used may vary considerably. Suffice it to say that the improved hand-rupturable crown cap may be 25 manufactured readily on a mass production basis and at 30 low cost according to well known basic manufacturing methods.

It is important to note that the steps of cutting the cap blanks from the strip material S and forming the crown caps out of the blanks do not impair the soldered 35 joint between the edges of slit 14. While the crimping operation imposes considerable stress on the cap material, the strength of the solder fillet is adequate to withstand these stresses, and yet it will not be so great as to resist tearing of the joint when a capped bottle is to 40 be opened by the described method using the tear tab 16. An otherwise conventional crown cap forming die may be used by providing a shallow groove or slit in the die to accommodate the upturned flanges of the slit 14. In fact, 45 the flanges are used to advantage in the blanking die since they may be used as an indexing means by which the positioning of the strip S may be maintained as it is advanced into the space between the blanking die elements, these flanged edges sliding in a slit leading into the die.

50 Preferably in or after the process of forming the dimple 16a in the tear tab 16 the tear tab 16 is bent at the lower edge of the cap (Figure 2) so that the convex surface of the dimple will be substantially flush with the lower edge of the cap and thereby facilitate 55 feeding of crown caps through bottling machinery. With the tear tab thus positioned preliminary to passing of the caps through bottling machinery no difficulty is encountered in securing proper alignment of caps with reference to feed guides and the like. When the cap is applied to a bottle as illustrated it is preferred that the tear tab be bent downwardly along the neck of the bottle where it will add no appreciable bulk to the capped bottle and will not interfere with its regular handling and storage.

60 The tear tab 16 may be dipped in a thermoplastic substance if desired for providing smooth gripping surfaces with rounded edges.

I claim as my invention:

65 1. A hand rupturable crown cap comprising a cap body including a circular top and a crimped annular skirt extending dependently therearound, said cap body having a single slit therein commencing at the edge of said skirt and extending substantially uninterruptedly therefrom upwardly across the width of said skirt and at least part 70 way across the top, said cap body being otherwise un-

weakened, a binder substance joining the slit edges together in a sealed joint extending continuously the length of said slit, and a handle element projecting from said skirt at a location adjacent the end of said slit to permit tearing of said slit joint by progressive shearing action applied through said handle element commencing at the end of said slit, said slit edges being flanged outwardly along the length of the slit to define a groove therebetween receiving a fillet of the binder substance.

2. The crown cap defined in claim 1, wherein the slit extends radially inward of the crown cap and terminates short of the center thereof.

3. A hand rupturable crown cap of sheet metal comprising a cap body including a circular top and a crimped annular skirt extending dependently therearound, said cap body having a slit therein commencing at the edge of said skirt and extending uninterruptedly therefrom upwardly across the width of said skirt and radially inward of said top, terminating short of the center thereof, the edges of said slit being flanged outwardly continuously along the length of said slit, a solder fillet joining the flanged edges of said slit together in a sealed joint extending continuously the length of said slit, and a handle element projecting from said skirt at a location adjacent the end of said slit to permit tearing of said slit joint by progressive shearing action applied to said handle element commencing at the end of said slit.

4. The hand rupturable crown cap defined in claim 3, wherein the handle element comprises an integral extension of the skirt adapted to lie close alongside the neck of a container carrying said cap, and to be bent outwardly therefrom for use as a pull tab in tearing open the slit joint in order to remove the cap from the container.

5. The hand rupturable crown cap defined in claim 4, wherein the pull tab has a dimple formed in the end thereof to facilitate grasping the same as a handle, said dimple having a convex side adapted to lie substantially in contact with the neck of the container.

6. A hand rupturable crown cap comprising a metal

30

35

40

cap body including a substantially circular top and a crimped annular skirt extending dependently therearound said cap body being slit from the edge of said skirt upwardly and across said skirt and inwardly of said top at least part way across said top, the slit edges being joined together by solder to form a sealed connection between said edges having strength sufficient to withstand the cap-forming operation, the slit edges being flanged outwardly to form a re-entrancy therebetween extending the length of the slit, and the solder comprising a fillet occupying said re-entrancy and presenting a surface inside the cap which is substantially flush with the inside surface of the cap.

7. A hand rupturable crown cap comprising a metal cap body including a substantially circular top and a crimped annular skirt extending dependently therearound, said cap body being slit from the edge of said skirt upwardly and across said skirt and inwardly of said top at least part way across said top, the slit edges being joined together by solder to form a sealed connection between said edges having strength sufficient to withstand the cap-forming operation, the slit edges being flanged outwardly to form a re-entrancy therebetween extending the length of the slit, and the solder comprising a fillet occupying said re-entrancy and presenting a surface inside the cap which is substantially flush with the inside surface of the cap.
